UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

PISTON DISTRIBUTION-VALVE.

1,308,001.

Specification of Letters Patent. Patented June 24, 1919.

Application filed January 2, 1917. Serial No. 140,141.

To all whom it may concern:

Be it known that I, CHARLES W. DAKE, a citizen of the United States, residing at Chicago, in the county of Cook and State of Illinois, have invented a certain new and useful Improvement in Piston Distribution-Valves, of which the following is a specification.

My invention relates to improvements in distribution valves for steam engines and the like, and has for one object to provide a new and improved form of cylindrical shell-type piston valve. In my form of valve the steam or vapor which is being controlled, passes through a valve seat which is ported, and these ports are opened and closed by the valve itself. In my preferred form each valve has one or more exhaust edges and one or more advance and cut-off edges, which I prefer to term generally the working edges of the valve. The valve reciprocates in this valve seat and on either side of the port in the valve seat are compression packing spring rings. These rings grip the valve and are in slidable engagement therewith. So long as the valve body itself is in engagement with these rings, they maintain their position, but, as the valve reciprocates, means must be provided to hold these rings in position against the compression port which they exert when the valve proper has been withdrawn from their grip. The means which I provide takes the form of a skirt on either side of each valve member, or either side of each valve working edge. These skirts are of the same diameter as the valve, and are carried from the valve by a series of bridging members or fingers. Fingers extend forwardly from these skirts toward the working edges, terminating, however, short of the working edges so as to permit the working edge to extend freely and continuously about the entire peripherly of the valve. The distance between the ends of the fingers however, and the working edges, is such that there is no possibility of the spring ring dropping out of position as the valve reciprocates. Of course the presence of these fingers in the passage at the outer ends of the valve travel is of no particular moment, as there is ample valve opening at such times, but it is exceedingly important that the working edge should be free and unobstructed, because at the instant when the contact is made and

broken, the instant when the passage is opened or closed, it is important that the valve have the maximum possible area, and my arrangement provides for such a situation.

My invention is illustrated more or less diagrammatically in the accompanying drawings, wherein—

Figure 1 is a section through a part of a steam engine cylinder and valve chest showing the valve partly in section and partly in elevation.

Fig. 2 is a section along the line 2—2 of Fig. 1.

Fig. 3 is a detail of the ring and bearing block.

Fig. 4 is a bottom view of a portion of a modified form or valve;

Fig. 5 is a section along the line 5—5 of Fig. 4.

Like parts are indicated by like figures in all the drawings.

A is a steam engine piston, adapted to reciprocate within a cylinder A¹. Steam passages A², A³ lead from either end of the steam engine cylinder to the valve chest A⁴. Steam is supplied to the valve chest through the passage A⁵ and distributed toward both ends to supply the passages A², A³ by the valve which will subsequently be described, the discharge of the exhaust steam not being shown, but it is understood of course that the steam will be discharged from the two ends of the valve chest. The valve chest contains adjacent both ends a valve seat made up of the cylindrical valve rings A⁶, A⁷. These rings are separated by an annular groove A⁸ in the wall of the valve chest, and this groove is indicated at the passages A² and A³. The presence of these two lining rings results in the formation of two annular ports in the valve seat one connecting with each end of the engine cylinder. These two ports are bounded on either side by spring compression rings A⁹. These spring compression rings are contained within the walls forming the valve seat and abut at either end at the bottom of the seat upon a filling block A¹⁰ upon which the valve rides. The relation of the filling block, the rings and the valve, as subsequently will be pointed out, is such that the rings closely grip the valve and make the steam-tight connection between it, but they are held by their position in the valve seat

against longitudinal movement, and slide with respect to the valve.

B is the valve body. It contains a wrist pin B¹ upon which is pivoted a valve stem B² which stem is adapted to be reciprocated in unison with the piston by any suitable means not here illustrated. The valve body is expanded or bell-shaped at either end as shown at B³, and these expanded ends carry cylindrical valve members B⁴ at either end, there being one valve member B⁴ for each port A⁸. Each of these valve members has an exhaust edge B⁵, and an advance and cut-off edge B⁶, and these members bear upon the block A¹⁰, and are surrounded by the packing rings A⁹, so that as the valve reciprocates the passage or movement of the steam is controlled. Obviously as the valve moves toward the left from the position shown in Fig. 1, the exhaust edge will open the port A⁸ and the steam will discharge from the cylinder through the pipe or passage A² into the exhaust. At the same time the advance and cut-off edge on the other end of the valve will move to open the passage to permit live steam to pass through the passage A³ into the other end of the cylinder. This operation continues as the engine valve gear is operated.

In order to prevent a collapse of the spring rings when the valve proper is drawn from engagement with them, the skirts C, C¹ are provided on either end of the valve. These skirts are cylindrical members of the same size as the valve itself. They are connected to and supported thereby by means of reinforcing ribs C³, which ribs are cut away as indicated at C⁴ so as to be removed a considerable distance from the effective working edge of the valve. These ribs being of considerable depth, stiffen the valve and the members C, C¹, and result in a rigid structure moved back and forth holding the ring in position. It will be noted, however, that the width of the port A⁸ is greater than the width of the spring ring, therefore in order to give the steam an opportunity to pass unobstructed through the ports, it is necessary to have the members C, C¹ as far removed from the working edge, and fingers C⁵ extend inwardly toward the working edges from the members C, C¹. These fingers decrease in width as they approach toward these edges and stop short of the edges as indicated. It will be understood that thus a maximum opening is given immediately adjacent the working edges, and the opening decreases away from the working edges. This does no harm, because the tapering supporting fingers encroach only upon that portion of the valve opening effective at the full length of valve movement when the opening is wide and there is no danger of insufficient valve opening. The distance between the ends of these fingers

and the working edges of the valve is such that there is no possibility of the compression rings dropping down in. Preferably I make this distance less than one-half the width of the compression ring, measured in a line parallel with the axis of the valve, though obviously this distance is not necessarily of the greatest moment, and little portions might easily be changed without in any way interfering with the operation of the device.

An inspection of Fig. 2 will show that the block A¹⁰ is such that its two ends are in line with the two lower ribs. The spring rings, therefore, are supported by the two lower fingers in line with the two lower ribs, and thus there is no possibility of leakage between the ends of the bearing block and the spring fingers, and the spring fingers are supported and positioned, and there is no possibility of their slipping up or springing up to interrupt or interfere with the operation of the valve.

In the modified form shown in Fig. 5, the bearing block D is much narrower than the block A¹⁰, and in this case the lower fingers D¹ terminate in extension members D², which actually bridge the gap and reach clear over to the working edges of the valve, the working edges being free at all points except at the immediate bottom.

It will be obvious that my device is illustrated in a more or less diagrammatic and general way, and that many changes might be made both in size, shape and arrangement of parts without departing materially from the spirit of my invention, and I wish, therefore, that my drawings be regarded as in a sense diagrammatic.

The use and operation of my invention are as follows: —

The piston reciprocates in the usual way driving the engine. The valve is caused to reciprocate by the valve gears operated by the engine in the usual manner. These parts except the valve stem and piston do not do anything because they form no part of my invention. The steam is admitted to the steam chest in the usual way and is distributed from it first to one end and then to the other end of the cylinder and causes the piston to reciprocate and the exhaust steam is discharged in the usual way.

The piston itself is a thin walled light symmetrical casting which consists merely in a cylindrical body portion with a flared or bell-shaped end carrying cylindrical valve portions. The cylindrical portions I have shown separated at either end of a dumb-bell. The structure might obviously be different. The point is that at each end of each cylindrical valve portion is a sharp working edge, one edge is the exhaust edge, the other the advance and cut-off edge. There are two such edges for each end of

the cylinder, that is to say, the advance and cut-off edge and the exhaust edge. As the piston valve reciprocates the exhaust edge on one end permits steam to exhaust from 5 that end at about the same time the advance and cut-off edge at the other end makes the live steam end of the cylinder.

The valve is surrounded by two spring packing rings at either end. These spring 10 packing rings form what is in effect part of the valve seat and the inclosing cylinders which support these rings merely form supports and abutments for the springs themselves which are in actual fact operating 15 portions of the valve seat. These spring rings grip the valve cylinder being pressed thereagainst both by their own tension and the steam in the usual way. The weight of the valve is supported on the bearing 20 block at either end at the bottom and this block is in effect part of the spring pressed valve seat since the spring rings abut at either end upon the rings of the block. The effective portion of the valve at either end 25 is only a little longer than the width of the port in the valve seat and as it moves back and forth first one and then the other ring comes out of contact with the valve. Means must, therefore, be provided to hold 30 these rings in position until the valve returns as otherwise the operation of the valve would be interrupted. These means take the form of a skirt or extension on either end of the valve of the same diameter 35 as the valve, but this skirt or extension must be spaced away from and separated from the effective working edges of the valve as otherwise the valve area at the lower load line or short cut-off will be fatally reduced. In my preferred form, 40 therefore, I support these members by ribs which are cut away adjacent the working edges of the valve but furnish a support for the parts and tie them together. In 45 order, however, that the spring rings may not fall down in between these members and the working edges of the valve, I provide fingers extending toward the working 50 edges. These fingers terminate short of the working edges which are tapered so that at the shorter valve travel they will furnish a minimum of obstruction for the passage of the steam, whereas as they widen toward that part of the valve exposed at 55 larger travel no harm is done because ample port area is available.

I claim:

1. A cylindrical piston valve and means for reciprocating it, a seat therefor including compression spring rings inclosing and in slidable contact with the valve, and means movable with the valve comprising an apron of the same diameter as the valve, and spaced away from the working edge 60 of the valve for holding said rings in posi-

tion, fingers extending inwardly from said apron toward the working edges of said valve.

2. A cylindrical piston valve and means for reciprocating it, a seat therefor including compression spring rings inclosing and in slidable contact with the valve and means movable with the valve comprising an apron, of the same diameter as the valve, and spaced away from the working edge 70 of the valve for holding said rings in position, supporting ribs interposed between the apron and the valve, said ribs being cut away adjacent the edge of the valve, to provide an opening about the substantially 75 entire periphery of the valve immediately adjacent the working edge, fingers extending inwardly from said apron toward the working edges of said valve.

3. A cylindrical piston valve and means for reciprocating it, a seat therefor including compression spring rings inclosing and in slidable contact with the valve, and means movable with the valve comprising an apron of the same diameter as the valve, and spaced 80 away from the working edge of the valve for holding said rings in position, fingers extending inwardly from said apron toward the working edges of said valve, said fingers decreasing in width toward the valve. 85

4. A cylindrical piston valve and means for reciprocating it, a seat therefor including compression spring rings inclosing and in slidable contact with the valve, and means movable with the valve comprising an apron 100 of the same diameter as the valve, and spaced away from the working edge of the valve for holding said rings in position, supporting ribs interposed between the apron and the valve, said ribs being cut away adjacent the edge of the valve, to provide an opening about the substantially 105 entire periphery of the valve immediately adjacent the working edge, fingers extending inwardly from said apron toward the working 110 edges of said valve, said fingers decreasing in width toward the valve.

5. A cylindrical piston valve and means for reciprocating it, a seat therefor including compression spring rings inclosing and in 115 slidable contact with the valve, and means movable with the valve comprising an apron of the same diameter as the valve, and spaced away from the working edge of the valve for holding said rings in position, fingers extending inwardly from said apron toward the working edges of said valve, said fingers terminating at a point removed from the working edge of the valve. 120

6. A cylindrical piston valve and means for reciprocating it, a seat therefor including compression spring rings inclosing and in slidable contact with the valve, and means movable with the valve comprising an apron of the same diameter as the valve, and spaced 125

away from the working edge of the valve for holding said rings in position, supporting ribs interposed between the apron and the valve, said ribs being cut away adjacent the edge of the valve, to provide an opening about the substantially entire periphery of the valve immediately adjacent the working edge, fingers extending inwardly from said apron toward the working edges of said valve, said fingers terminating at a point removed from the working edge of the valve.

7. A cylindrical piston valve and means for reciprocating it, a seat therefor including compression spring rings inclosing and in slidable contact with the valve, and means movable with the valve comprising an apron of the same diameter as the valve, and spaced away from the working edge of the valve for holding said rings in position, fingers extending inwardly from said apron toward the working edges of said valve, said fingers decreasing in width toward the valve, said fingers terminating at a point removed from the working edge of the valve.

8. A cylindrical piston valve and means for reciprocating it, a seat therefor including compression spring rings inclosing and in slidable contact with the valve, and means movable with the valve comprising an apron of the same diameter as the valve, and spaced away from the working edge of the valve for holding said rings in position, supporting ribs interposed between the apron and the valve, said ribs being cut away adjacent the edge of the valve, to provide an opening about the substantially entire periphery of the valve immediately adjacent the working

edge, fingers extending inwardly from said apron toward the working edges of said valve, said fingers decreasing in width toward the valve, said fingers terminating at a point removed from the working edge of the valve.

9. A valve comprising a housing, steam ports therein, annular valve seat rings separate one from another located within said housing on opposed sides of said ports, spring packing rings mounted within said seats bounding said ports, a hollow piston valve slidable within said valve seat and yieldingly gripped by said spring rings, said piston valve having a cylindrical extension integral therewith, and a working edge, a piston rod located within the hollow piston out of contact and removed from the cylindrical extension, an apron in opposition to the working edge adapted when the working edge is out of register with the spring ring to hold the ring in position, ribs interposed between the cylindrical member and the apron cut away at the working edge removed from the piston rod for holding the apron and cylindrical member in fixed relation, and fingers projecting forwardly from the apron in register with said ribs and terminating short of the working edge.

In testimony whereof I affix my signature, in the presence of two witnesses, this twenty-eighth day of December, 1916.

CHARLES W. DAKE.
